GEORGE B. WURSTER, OF NEW YORK, N. Y., ASSIGNOR TO W. R. OSTRANDER & COMPANY, OF NEW YORK, N. Y., A CORPORATION OF NEW YORK.

ELECTRIC-BELL MECHANISM.

1,054,379.

Specification of Letters Patent. Patented Feb. 25, 1913.

Application filed April 26, 1912. Serial No. 693,321.

To all whom it may concern:

Be it known that I, GEORGE B. WURSTER, a citizen of the United States, and resident of New York, in the county of Westchester and State of New York, have invented certain new and useful Improvements in Electric-Bell Mechanism, of which the following is a specification.

My invention relates particularly to what are commonly termed single stroke signal or alarm gongs.

The object is to provide a construction which will give a powerful stroke and require only a minimum consumption of current.

Briefly considered the invention contemplates the use of an electro-magnet, a pivoted armature and a striker pivoted to the armature so that a small movement of the armature is multiplied in the movement of the striker. To facilitate this movement the striker is in the form of a lever, the short end of which has a roller which travels on a guide plate. A yielding stop is provided for the armature and this stop may be adjusted to vary the action of the striker.

Figure 1 is a front view of mechanism embodying the improvements of my invention showing in dotted lines the position of the armature and striker in the act of striking. Fig. 2, is a side view of the armature and striker. Fig. 3, is a side view of a modification of the armature and striker. Fig. 4, is a front view of the construction of Fig. 3.

The base or frame 1 is of suitable construction adapted to be secured to a support in any suitable manner as is customary in devices of this character. The bell or gong 2 is secured to the frame in any suitable manner.

The electro-magnets 3 are of suitable usual construction supported by the frame 1. The armature 4 is pivoted at 5 and is adapted to be attracted by the electro-magnet. A contact screw 6 may be adjusted to vary the relative initial position of the armature. The electrical connection may be made in any suitable manner as is customary in this art.

Ordinarily the striker is a part of or formed as a prolongation of the armature so that the angular movement of the striker is the same as the angular movement of the

armature. It has also been proposed to pivot the striker independently of the armature and connect it to the armature by some form of link. This type of mechanism introduces additional friction and lost movement as well as complications in construction. By my invention the striker 7 is pivoted at 8 to the upper end of the armature 4 and the lower end of the striker is provided with a roller 9 which bears against the track plate 10 on the head of the electro-magnet. The striker is therefore a lever whose short arm carries the roller 9 and whose long arm carries the hammer 11.

When a magnet is energized the armature 4 is drawn suddenly toward it thus drawing the pivot 8 to the left as viewed in Fig. 1. This causes the striker to turn on its pivot 8, the roller 9 traveling a very short distance down the track plate 10. This throws the outer end of the striker and hammer 11 toward the gong. It is possible in this way by only a slight movement of the armature 4 to obtain a wide swing of the striker. This is of particular advantage when it is realized that the operation of a magnet is most efficient when the armature is nearest to it and that it requires an exceedingly powerful magnet and the consumption of a large amount of current to start the armature which is initially located at a considerable distance from its magnet. I also provide a yielding stop 12 for instance of rubber, felt or other yielding material for the striker as the striker rebounds from the gong. This stop is carried by an arm 13 which extends through the post 14 and is clamped by a screw 15. In this way the arm may be adjusted so as to vary the position of the stop and action of the striker. To prevent the striker from getting out of place relative to the armature a bar 17 may be provided as shown in Figs. 1 and 2.

It is preferable to so locate the magnet, armature, striker and gong that when the armature is drawn over against the magnet, the bar 17 will act as a stop for the lower end of the striker but the momentum of the hammer end of the striker will carry the hammer against the gong. The armature and striker are then substantially in a straight line and act as if in one piece so that the blow will be resonant. When the blow is struck the hammer springs away

from the gong slightly even though the magnet continues to be energized and continues to hold the armature against it.

By the construction thus shown and described with the frame up-right as shown in Fig. 1 it is unnecessary to use any spring in connection with the striker or the armature. This has a particular advantage in that the springs which are customary to use for the purpose of retracting the armature and striker necessitate power in the magnets to over-come the springs in the striking action. By my construction the armature and striker will rebound and remain retracted without the use of springs. If at any time it should be necessary to install this construction in a position such that the parts would not normally remain in their proper retracted position it is obvious that a spring or springs might be employed in the manner common in this art.

In the form shown in Figs. 1 and 2 the end of the armature is forked to receive the end of the striker. In Figs. 3 and 4 the end of the striker is forked to receive the end of the armature and two rollers 18 and 18 are provided in place of the single roller 9. It will be obvious that other modifications may be made without departing from the spirit or scope of my invention.

What I claim is:—

1. In an electric bell mechanism, an electromagnet, an armature, a striker pivotally carried by the armature, a track plate and a roller carried by the striker and engaging the track plate.

2. In an electric bell construction, an electromagnet, a pivoted armature therefor, a striker pivoted intermediate its ends to the armature, a track plate at the head of the

magnet, the inner end of the striker engaging said track plate and a stop for said striker.

3. In an electric bell construction; an electro-magnet, an armature therefor, a striker pivoted intermediate its ends to said armature, an abutment for the inner end of said striker, a hammer at the outer end of said striker and means independent of the abutment and of the gong for limiting the stroke of the striker in advance of the armature.

4. In an electric bell construction, a magnet, an armature, a striker pivoted intermediate its ends to the armature, a stop carried by one of said last named two elements and engaging the other for checking the striker and an abutment for the inner end of said striker, said striker being adapted to be brought into line with said armature at the striking position.

5. In an electric bell construction, a magnet, an armature, a striker pivoted intermediate its ends to said armature, an abutment for the inner end of said striker between said armature and said magnet and a roller interposed between said abutment and said striker during the entire ringing stroke.

6. In an electric bell construction, a magnet, an armature therefor, a striker pivoted intermediate its ends to the armature, an abutment for the inner end of said striker, a post, an adjusting screw for the armature carried by said post and an adjustable stop for the striker carried by said post.
